UNITED STATES PATENT OFFICE.

AUGUST HILFIKER, OF SALEM, OREGON.

PRUNE-TREATING MACHINE.

1,346,315.

Specification of Letters Patent. Patented July 13, 1920.

Application filed September 12, 1919. Serial No. 323,239.

To all whom it may concern:

Be it known that I, AUGUST HILFIKER, a citizen of the United States, residing at Salem, in the county of Marion, State of Oregon, have invented certain new and useful Improvements in Prune-Treating Machines; and I do hereby declare the following to be a full, clear, and exact description of the invention, such as will enable others skilled in the art to which it appertains to make and use the same.

This invention may be said to relate to shaking trays for drying fruit, although it includes in its construction washing and rinsing means which render the drying desirable. More particularly the machine is employed in the treatment of prunes whose drying, after they are washed, takes place on trays whereon it is desirable to spread the prunes accurately in a single layer, although I reserve the right to use the machine for any purpose of which it is susceptible. Details are set forth in the following specification and claims, and reference is made to the drawings wherein:

Figure 1 is a left side elevation,

Fig. 2 a central longitudinal section,

Fig. 3 a plan view,

Fig. 4 a right side elevation,

Fig. 5 a transverse vertical section through the heater on the line 5—5 of Fig. 1,

Fig. 6 a transverse section on the line 6—6 of Fig. 1.

This machine comprises as its principal elements a heater at its rear end, and if the machine be employed in certain arts the heating process could be extended to the point of cooking the fruit or other articles treated; a pan hanging normally within the heater but capable of movement to carry the articles therefrom into a tank or tub which may contain water or other liquid for washing or rinsing the heated articles, or in some cases for cooling them; an elevator so constructed that the articles are carried upward and forward out of the tank in a single stratum and in orderly rows across the machine, and from which elevator they are delivered to a tray; a shaking support for holding this tray and giving it the proper vibration to receive the articles from the elevator and spread them out upon it in a single stratum, and from which shaking support the tray can be removed when full and replaced by another; and the mech-

anism for actuating and controlling the several elements. The machine is so constructed that an operator stands at the front end thereof where he can remove the filled tray and replace it with another one, and from which point he can control the action of parts, while an attendant at the rear end of the machine has charge of the heater and will fill the pan from time to time; although on small plants it is possible that one operator may perform both functions.

The heater as herein shown comprises a fire box 1 above a grate 2, and an ash pit 3 beneath said grate. A tank 4 stands above the fire box and preferably contains heads 5 connected by flues 6 so that the heating of the water in the tank is thorough. A pan 7 is hinged at 8 and has a perforated bottom which hangs normally within the tank, permitting the prunes or other articles to be submerged in the water as will be clear; and a rope 9 leads from the free edge of the pan upward over pulleys and forward to within reach of the operator standing at the front of the machine. This description of the heater applies to what is shown in the drawings, although of course any appropriate heater might be employed. I prefer, however, that the pan have means for dumping the heated articles from the tank into the tub described below, and that the dumping action be controlled from the front end or side of the machine.

Supported in a suitable frame 10 is a tank or tub 11 which is preferably of metal and has its bottom 12 inclined upward and forwardly, and appropriate pipes (not shown) will be provided for admitting cold and fresh water and replacing it from time to time when necessary. The frame may be a separate structure standing adjacent the brickwork or masonry of the heater but this detail is unimportant. Pivotedly mounted at its lower end within the tub is the frame 13 of an elevator leading upward over said bottom, and by preference the elevator is composed of upper and lower shafts 14 and 15 carrying sprocket wheels 16 over which run a pair of endless chains 17, the latter carrying buckets 18. These are preferably of L-shaped cross section as seen in Fig. 2, their inner leaves underlying the prunes and their outstanding leaves being spaced from each other a distance to admit only one row of such prunes so that surplus prunes roll 110

back into the tub against a strip 19 fixed across its rear lower corner. Therefore the elevator automatically selects and carries upward a single stratum of prunes.

- 5 Hingedly mounted within the frame 10 under the delivery end of the elevator is an apron or lip 20 onto which fall the prunes carried up by the elevator. Secured within the lower part of the frame and extending well under this lip is a pan 21 for catching the drippings, and this pan will have an outlet at an appropriate point not necessarily shown. Across the drip pan are fixed two rods 22 and 23, from the former of 15 which rise links 24 and from the latter of which rise other links 25, these preferably being adjustable in length by means of turn buckles 26 or other appropriate means. The upper ends of the links are connected in 20 pairs by rods 27 and 28 respectively, said rods supporting a frame 29 which stands above the pan 21 and has a lip 30 at its rear end underlying the lip 20 and receiving prunes therefrom. The side bars of this 25 frame have cleats 31 on which is removably supported a perforated or reticulated tray 32. A link 33 leads from one of said rods 28 and connects with a crank 34 on the main shaft 35, said shaft having a pulley 36 connected by a belt 37 with the power pulley 38 which is rotated by belting as indicated at 39. Therefore when the main shaft is 30 rotated, the shaker frame 29 is reciprocated back and forth, the links 24 and 25 supporting it above the pan 21, and the adjustability of the links 25 permitting the shaker frame and therefore the tray within it to be set level or to be inclined slightly as desired.
- 35 40 Intermeshing gears 40 and 41 connect the main shaft 35 with a countershaft 42 journaled through the frame 10, and a small gear 43 on one end of this shaft engages a large gear 44 on the corresponding end of 45 the upper shaft 14 of the elevator, whereby motion is transmitted from the power shaft thereto. Said shaft 14 rests in open bearings 45 at the top of the frame 10, and adjacent that end which carries the gear 44 50 a lever 46 is pivoted to the frame as best seen in Fig. 4. By preference this is a bell-crank lever, its short arm carrying a yoke 47 underlying the shaft, and its long arm being connected by a link 48 with a hand lever 49 pivoted to the frame 10 adjacent the front end thereof. By movement of this hand lever the bell-crank lever 46 is rocked on its pivot and the yoke 47 raises this end of the shaft 14 in the open bearing 55 60 45 so that its gear 44 is lifted out of mesh with the gear 43 and movement of the elevator interrupted while the hand lever is held, without necessarily stopping the movement of the main shaft and the vibration of the shaker. A spring 50 normally

draws this end of the elevator frame 13 downward so as to reengage the gears 43 and 44 when the hand lever 49 is released.

65 The power shaft 55 carrying the main pulley 38 is mounted in a frame 51 which is pivoted at 52 within the main frame 10, and a bar or tongue 53 extends from the frame forward. The front end of this tongue is connected by a link 54 with a crank 56 on a rock shaft 57 mounted in bearings across 70 the front end of the main frame, and a hand lever 59 rises from the shaft 57 within convenient reach of the operator. This constitutes one means for loosening the belt 37 connecting the power pulley 38 with the 80 pulley 36 on the countershaft, and it will be obvious that by drawing on the hand lever 59 the frame 51 and power shaft are raised so that the rotation of the latter is not interrupted but it is not communicated to the 85 countershaft while the hand lever is so held. By this means it will be obvious that the reciprocation of the shaker 29 and the movement of the elevator can both be checked without stopping the rotation of 90 the power shaft or disconnecting the machine from the motor. Therefore the operator standing in front of this machine has control through the lever 49 of the movement of the elevator, or through the 95 lever 59 of the movement of both the shaker and the elevator. It is obvious that he would not care to interrupt the movement of the shaker and permit the elevator to continue its function.

100

95 From time to time a charge of prunes or other articles to be treated is placed within the heating tank 4, with the result that the articles are heated or cleansed, or perhaps in some cases cooked. Drawing on the rope 9 105 raises the pan on its hinge 8 and dumps its contents into the tub 11 which latter contains water to rinse the prunes or articles, and probably cold water for the purpose of cooling them. Movement of the elevator 110 now causes its scrapers to successively engage single rows of prunes at the bottom of the tub, which rows are drawn upward over the bottom plate 12 and delivered one by one onto the lip 20. The latter drops the prunes 115 onto the lip 30 which is vibrating with the shaker frame 29, and this lip in turn drops the fruit onto the tray which also is moving with the frame; and the movement of the latter and the adjustment of the tray cause 120 the fruit to be spread out over the surface of the tray in a single stratum. Meanwhile the water thereon drips through the screen bottom of the tray into the pan 21, and is carried off to waste as will be understood. 125 The operator standing at the front end of the machine has full control over the various elements as already explained, while an attendant from time to time replenishes the 130 charge of prunes in the pan 7; but, if the

115

120

125

130

machine is not too large, the single operator can leave his place in front and himself replenish the pan after each dumping. The rope is so attached to the front end of the 5 pan that it turns the same over its hinge to dumping position, while the next pull on the rope turns it back and drops it into the tank 4.

What is claimed is:

- 10 1. In a machine of the type described, the combination with an elevator of a fixed pan underlying the delivery end of said elevator, cross rods therein, links rising from the rods in pairs, a shaker frame having cross rods carried by the upper ends of the links, means on the frame for holding a receptacle into which said elevator delivers, means for 15 adjusting the length of one pair of links, and driving and controlling mechanisms for 20 the elevator and shaker.
2. In a machine of the type described, the combination with a tank, and elevating means leading upward from said tank; of a lip under the delivery end of said elevator, 25 a fixed drip pan beneath the lip, a frame movably supported above said pan and having a second lip underlying the first, a strainer tray in said frame above the pan and extending under the second lip, means 30 for driving the elevator and for agitating the frame, and controls for said means.
3. In a machine of the type described, the combination with a heater, a pan hinged thereon and adapted to drop into the heater 35 or to be turned outward on its hinges to dumping position, a cooling tank into which said pan dumps, and elevating means leading upward from said tank; of a lip under the delivery end of said elevator, a pan fixed 40 beneath the lip, a shaker frame movably supported above said pan and having a second lip underlying the first, cleats in said

frame for supporting a receptacle under the second lip, means for driving the elevator and for reciprocating the shaker frame, and 45 controls for said means.

4. In a machine of the class described, the combination with an elevator, and a power-driven shaft having a gear, the upper shaft of the elevator resting in open bearings and 50 having a gear meshing with that named; of a bell-crank lever pivoted at its angle, a yoke connected with one arm and underlying the elevator shaft, and a hand lever connected with the other arm of the bell- 55 crank lever, for the purpose set forth.

5. In a machine of the type described, an elevator, a shaker frame carrying a receptacle to which said elevator delivers, a crank shaft having its crank connected with said 60 frame for shaking the latter, a hinged frame, a power shaft therein, pulleys on the power shaft and crank shaft, a belt connecting the said pulleys, and manually operable means for swinging the frame to loosen the 65 belt.

6. In a machine of the type described, the combination with a tank, and elevating means leading upward from said tank; of a lip under the delivery end of said elevator, 70 a pan fixed beneath the lip, a shaker frame movably supported above said pan and having a second lip underlying the first, said frame supporting a receptacle under the second lip, means for driving the elevator 75 and for reciprocating the shaker frame and independent controls for said means.

In testimony whereof I affix my signature in the presence of two witnesses.

AUGUST HILFIKER.
